CLAIM

The ornamental design for a zig-zag photograph holder, as shown and described.

DESCRIPTION

FIG. 1 is a perspective view of a zig-zag photograph holder showing our new design;

FIG. 2 is a top plan view thereof;

FIG. 3 is a bottom plan view thereof;

FIG. 4 is a front elevation view thereof;

FIG. 5 is a side elevation view thereof; and

FIG. 6 is a perspective elevational view thereof when open.

The rear and side elevations thereof (not shown) when closed are identical to the front and side elevation views of FIGS. 4 and 5.

*FIG. 1**FIG. 2**FIG. 3*

FIG. 4

FIG. 5

FIG. 6
